UNITED STATES PATENT OFFICE.

JOHN SCHEMINGER, JR., OF PROVIDENCE, RHODE ISLAND, ASSIGNOR TO AETNA AUTOMATIC OIL BURNER, INCORPORATED, OF NEW YORK, N. Y., A CORPORATION OF NEW YORK.

LIQUID-FUEL-FEEDING DEVICE.

Application filed April 17, 1924. Serial No. 707,268.

To all whom it may concern:

Be it known that I, JOHN SCHEMINGER, Jr., a citizen of the United States, residing at Providence, in the county of Providence and State of Rhode Island, have invented 5 certain new and useful Improvements in Liquid-Fuel-Feeding Devices; and I do hereby declare the following to be a full, clear, and exact description of the invention, such as will enable others skilled in the art to which it appertains to make and use the same.

This invention relates to liquid fuel feeding devices, and more particularly to a valve 15 construction especially designed and adapted to be used in connection with pump-fed rotary oil burners, for feeding the liquid fuel in such manner that a portion thereof sufficient to maintain combustion is separated from the major portion and delivered to the burner unaffected to any appreciable extent by agitation or the pulsations of the pump, while the surplus or major portion is returned to the supply tank.

25 In the operation of pump-fed rotary oil burners, when the liquid fuel is conducted direct from the pump to the burner, the agitation or pulsatory action produced by the pump piston on the moving column of liquid seriously interferes with the operation of the burner, resulting at times in extinguishing the flame.

One object of my invention is to overcome 35 this difficulty and provide simple and efficient means for effecting a steady and uniform feed or flow of the liquid fuel from a pump to the burner, or other device with which the invention may be used, unaffected to any appreciable extent by the pulsations 40 of the pump, as in pump-fed liquid fuel burners as heretofore ordinarily constructed.

Another object of the invention is to provide a simple and efficient device of the character referred to, interposed in the pipe line 45 between the pump and the burner for feeding liquid fuel in such manner as to create the necessary back pressure acting on the fuel in the feed pipe in the manner set forth 50 in my Patent No. 1,442,785, dated January 16, 1923, for improvement in liquid fuel feeding means, without rendering it necessary to maintain a column of oil for this purpose as required in using the apparatus 55 described in said patent.

Differences to be noted between this and the 1923 patent are the following:

1. The valve is not provided with a

Other objects of the invention are to provide a device of the character referred to for effecting a separation of the oil in the manner set forth in my aforesaid patent, and in which the back pressure required to drive the fuel oil to the burner is developed within the device itself, thus eliminating the vertical liquid column heretofore used to create such pressure, and which, when thrown out of operation, will automatically and positively close the feed outlet to the burner, and which also enables the pressure in the feed line to be increased or decreased at will by means of interchangeable springs of different strengths.

60 The invention will first be hereinafter more particularly described with reference to the accompanying drawings, which are to be taken as a part of this specification, and then pointed out in the claims at the end of 65 the description.

In said drawings, Fig. 1 is a central vertical sectional elevation of a liquid fuel feeding device embodying my invention; showing 70 the valve mechanism in closed position;

Fig. 2 is a view similar to Fig. 1; showing 75 the valves open; and

Fig. 3 is a transverse horizontal section taken on the line 3—3 of Fig. 1, looking 80 downward.

85 The valve casing 1 is preferably of cylindrical form, as shown, open at its upper end and provided with a base-portion 2, for attachment to a supporting base; said base-portion having a clean-out opening therein, closed by a removable plug 4, to permit cleansing the oil chamber 5 at the bottom of the casing. Within the casing there is a valve chamber in which is placed a vertically movable valve 6 of disk-like form, which is normally held by gravity in closed 90 position slightly above the liquid supply pipe 7, leading from the pump (not shown) into the casing and is provided with a depending stem 12 which passes through a central opening in a guide plate 8, fixed within the casing and provided with a plurality of openings 9 through which oil 95 passes from above into the liquid space below and between said guide plate and a disk-like valve-supporting plate 10, which is driven or otherwise firmly secured within the casing and provided with a central 100 opening or port 11 adapted to be closed by the lower conical end 13 of the valve stem 105 and bottomed in the valve chamber.

110

seated upon the support 10 directly over said port 11. The bore of the casing is reduced below the plate 10 so as to form a shoulder upon which said plate may rest. The port 11 opens into the oil chamber 5 which is in communication with an oil feed pipe 14 leading to the burner. The disk valve 6 serves to close the valve chamber above the liquid fuel supply pipe 7 and is 10 pressed downwardly by a spring 15 placed between said valve 6 and the cover plate or top 16 of the casing, which is removably secured by set screws or the like, as shown, in order to permit the removal of the spring 15 and the substitution of a stronger or weaker spring, as desired, to increase or decrease the pressure on the valve 6. The spring 15 is adapted in operation to exert pressure opposed to the pressure of the liquid forced 20 into the casing or valve chamber by the pump to a greater or less degree, according to the strength of the spring used, and will yield to greater pressure exerted by the pump when the latter is in motion so as to 25 permit the valve to open. The spring tends to hold the valves 6 and 13 normally in their lowermost positions, in which the valves are closed, and serves to close the valves quickly when the pump is stopped, the spring it- 30 self being held under pressure between the valve 6 and the cover plate or cap 16. The upper portion of the bore of the valve casing through which the upper end of the spring passes is enlarged as shown in Fig. 35 1 to permit a free passage of oil around the spring and out through a surplus oil return pipe 17 leading from the valve casing to a storage tank or the oil reservoir from which the fuel supply is drawn by the 40 pump.

In operation, liquid fuel is drawn by the pump from a supply tank or reservoir (not shown) and forced through the pipe 7 into the valve casing, filling the oil chamber 45 above and below the guide-plate 8, through the holes 9 in the latter, and when sufficient pressure has been developed the valve plate 6 is raised and with it the valve 12 to the position shown in Fig. 2 of the drawing, 50 whereupon a portion of the liquid will pass through the port 11 into the oil chamber 5 and out through the feed pipe 14 to the burner, while the major portion or surplus fuel which is not needed to supply the 55 burner, and which is directly agitated by the pulsations of the pump, will pass up and out through a by-pass 18 into the pipe 17 and thence back to the storage tank, while the lesser portion of fuel under fluid pres- 60 sure produced by the pump in opposition to the pressure of the spring 15 is forced into and through the fuel feed-pipe to the burner. By these means oil is delivered to the burner practically free from agitation caused by the pulsations of the pump, and

under a pressure that may be quite accurately predetermined by the strength of the spring used to oppose the pressure exerted by the pump, the pressure exerted being greater or less according to the strength 70 of the spring and the speed at which the pump is operated. To facilitate the return of the valve to a closed position when the pump is stopped, the valve plate 6 has a small hole or vent 6^a formed therein through 75 which oil may escape through the piston valve, which is forced downwardly by the pressure of the spring to its lowermost position, as shown in Fig. 1.

It is understood, of course, that minor 80 changes may be made in the details and arrangement of parts without departing from the spirit and scope of my invention.

Having thus described my invention, what I claim as new and desire to secure by Letters Patent of the United States, is:

1. A liquid fuel feeding device comprising a casing having a differential bore, reduced in size at the lower end thereof, a piston valve slidably fitted in said bore and carrying a depending valve stem which passes through a partition or guide-plate secured within the casing so as to divide the oil space or chamber below said valve into upper and lower compartments, said guide-plate having a liquid fuel passage therethrough into the lower compartment, a spring interposed between said valve and the top of the casing and tending to normally hold said valve in closed position, a fuel supply pipe leading into said upper compartment, a partition plate within said casing below said guide-plate having an opening or discharge port therethrough on which the free end of said valve stem may 90 be seated to close said port, a fuel feed-pipe connecting said discharge port with a burner or other device for supplying oil thereto, and a discharge pipe at the upper end of the casing through which surplus fuel may be returned to the supply tank. 100

2. A liquid fuel feeding device comprising an upright substantially cylindrical casing having a differential bore of reduced size at its lower end, a piston valve slidably fitted in said bore, a spring interposed between said valve and the top of the casing and tending to normally hold the valve in closed position, a guide-plate secured within the casing below said valve so as to divide the interior of the casing into upper and lower compartments, said guide-plate having a plurality of restricted liquid fuel passages therethrough into the lower compartment, and a central opening through which passes a valve stem carried by said valve, a fuel supply pipe leading into said upper compartment below said valve, an oil chamber within the reduced portion of said casing at the lower end thereof below said guide-plate, 115 120 125 130

- a partition plate within said casing between said guide-plate and said oil chamber and having a central opening therethrough forming an outlet which is normally closed by
- 5 the free end of said valve stem, a fuel feed-pipe leading from said oil chamber to a burner or other device for supplying oil thereto, and a discharge pipe at the upper end of the casing through which surplus fuel
- 10 may be returned to the supply tank.
3. In a device of the character described, a substantially cylindrical casing having a piston valve slidably fitted therein, said valve having a stem passing downwardly
- 15 through a guide-plate secured within the casing and dividing the interior thereof below said valve into upper and lower compartments, said guide-plate having a liquid fuel passage therethrough into the lower
- 20 compartment, a fuel supply pipe leading into said upper compartment below said valve, a partition plate within said casing below said guide-plate having a central opening therethrough and providing a valve seat for the
- 25 free end of said valve stem, whereby said opening is normally closed, a fuel feed-pipe below said valve seat leading to a burner or other device for supplying oil thereto, a discharge pipe at the upper end of the casing
- 30 through which surplus fuel may be returned to the supply tank, and a spring interposed between the first named valve and the top of the casing and tending normally to hold both valves in closed position.
- 35 4. A device of the character described comprising a casing provided with a valve-chamber having a vertically movable valve therein, a liquid fuel supply pipe leading into said casing at one side of said valve, a
- 40 surplus fuel discharge pipe at the other side of said valve, said chamber having an apertured partition therein arranged to provide a fuel receiving compartment at one side thereof and a fuel delivery compartment at
- 45 the other side, and said valve having a stem which protrudes through said partition into said delivery compartment, the latter compartment having a bottom plate provided with an outlet port upon which the free end
- 50 of said valve stem is adapted to be seated so as to normally close said port, a feed pipe in
- said casing through which a portion of the liquid entering said chamber may be forced out, and pressure-applying means acting on said valve in opposition to the pressure of the liquid entering the casing through said supply pipe, whereby a portion of the liquid fuel entering said valve chamber is forced out through said feed pipe while the larger portion or surplus fuel is discharged through
- 55 60 65 70 75 80 85 90 95
- said surplus fuel discharge pipe.
5. A device of the character described comprising an oblong vertically disposed casing of substantially cylindrical form provided with a valve-chamber having a vertically movable valve therein, and a liquid fuel space above said valve, a liquid fuel supply pipe leading into said casing at one side of said valve, a surplus fuel discharge pipe at the other side of said valve leading from said fuel space, said chamber having an apertured partition therein arranged to provide a fuel receiving compartment at one side thereof and a fuel delivery compartment at the other side, and said valve having a stem which protrudes through said partition into said delivery compartment, the latter compartment having a bottom plate provided with an outlet port upon which the free end of said valve stem is adapted to be seated so as to normally close said port, a liquid fuel settling chamber being provided between said bottom plate and the lower end of the casing, a fuel feed pipe leading from said settling chamber through which a portion of the liquid entering said valve chamber may be forced out, and pressure-applying means acting on said valve in opposition to the pressure of the liquid entering the casing through said supply pipe, whereby a portion of the liquid fuel entering said valve chamber is forced out through said feed pipe while the larger portion or surplus fuel is discharged through said surplus fuel discharge pipe.

In testimony whereof I affix my signature in the presence of two witnesses.
